JOHN A. COLE, OF NEW YORK, N. Y.

QUICK-ACTION ELECTRIC SWITCH.

1,045,773.

Specification of Letters Patent. Patented Nov. 26, 1912.

Application filed August 30, 1911. Serial No. 646,841.

To all whom it may concern:

Be it known that I, JOHN A. COLE, a citizen of the United States, residing at the city of New York, in the borough of Queens and State of New York, have invented certain new and useful Improvements in Quick-Action Electric Switches, of which the following is a full, clear, and exact description.

This invention relates to electric switches, and has for one of its objects the provision of an improved positively acting mechanism for abruptly opening and closing such switches.

Another object of my invention is to so dispose the operative parts of the device that the contact elements and substantially all of the said mechanism may be positioned to the rear of a switchboard, leaving but little more than the switch handle and its supporting bracket upon the front of said board.

A further object of my invention is to so arrange the movable contact elements of my switch that they are aided in action by gravity.

My invention contemplates the inclusion in the switch operating mechanism above referred to, of toggle acting parts and the combination therewith of spring impelled elements which insure the unfailing operation of the device.

These and other objects of my invention will be hereinafter described and more particularly set forth in the appended claims.

In the drawings which form a part hereof and in which like reference characters designate like parts throughout the several views: Figure 1 is a vertical longitudinal section of a switch constructed in accordance with the principles of my invention. Fig. 2 is a vertical transverse section taken on the line II-II of Fig. 1. Fig. 3 is a vertical transverse section taken on line III-III of Fig. 1. Fig. 4 is a small scale illustration of the switch parts and operating mechanism with the switch in closed position.

The switchboard proper has been broadly designated 1, and has secured to the front thereof a bracket 2 which is provided with outstanding lugs 3 through which extends the shaft or pin 4 upon which the operating lever 5 is mounted. Upon the rear side of the switchboard is mounted a second bracket 6 which indirectly supports the contacts. An extension 7 of bracket 6, which projects rearwardly from the base thereof carries an

insulating base block or plate 8, the extension 7 being preferably bifurcated to provide arms 9 to which said plate is secured in any suitable manner. The plate 8 is preferably provided with alined apertures 10 disposed adjacent the center thereof for the reception of threaded thimbles 11 which are secured firmly in position by means of nuts 12; said nuts in the exemplification shown being received into a recess 13 into which open the recesses 10, above referred to. Suitable plastic insulating material 14 may be poured around these nuts when in position, securing them against inadvertent displacement, and also providing insulation therebetween. Washers 15 are also preferably provided in connection with these nuts; being also embedded in the plastic insulating mass. A U-bolt 16 extends through the thimbles 10 and is freely movable longitudinally therein, the lower extremities of the arms of this bolt being threaded as at 17 to afford means for securing an insulating block 18 thereupon; this block being adjustably held upon the U-bolt in any desired position by means of washers 19 and nuts 20. Block 18 carries somewhat Y-shaped metallic blocks 21 upon either side thereof, which blocks in turn carry the preferably V-shaped leaves 22 which constitute the movable contacts. These leaves may be of copper or other suitable material, and should have considerable elasticity so that when their upper edges are driven against the fixed contact pieces 23, the legs of the V's will be spread apart thereby effecting very perfect electrical connections at the respective points of contact. The leaves are held firmly in position in the blocks 21 by means of triangular clamping blocks 24; screws 25 being threaded into the bases of blocks 21 to this end. The outermost V-shaped leaf 26 may be made of slightly heavier gage metal than the inner leaves, and is also preferably provided at its contact making edges with beads 27 to obviate any possibility of such leaves buckling, as after considerable use the contact making surfaces of the pieces 23 may become slightly roughened or burned. The burning of such surfaces is a remote possibility, however, since the switch parts in operation make and break contact so quickly that arcing is substantially eliminated.

The contact pieces 23 may be secured to

the block 8 in any suitable manner, and are preferably L-shaped, the outstanding shorter legs of such members being adapted to be drawn firmly into contact with the depending stems 28 of the terminals 29. The bodies 5 of these terminals are disposed in recesses 30, preferably adjacent either end of the block 8, said terminals being adapted for the usual soldered connection with the extremities of the lead wires. In the particular 10 switch exemplified, upon the upper side of the block 8 and between the arms 9 of the bracket 6, are two toggle brackets 31, one such bracket being upon either side of the center line of the said block, and these brackets carry a pin 32 which may be secured therein in any suitable manner, as by means of split coppers 33; said pin 32 carrying the links 34 which form the lower 15 portions of toggles, broadly designated 35, the upper links of these toggles being respectively designated 36. The upper extremities of links 36 are apertured for the reception of a pin 37 which may be held in 20 position by split coppers 33 in like manner to pin 32. Between the links 36 is a lever 38 through which the pin 37 extends; the inner end of said lever being pivotally mounted at 39 between the ears 40 of a small 25 bracket 41. This bracket 41 is adjustable vertically with respect to bracket 6, being clamped thereagainst by means of screws 42; the holes 43 in the base of bracket 41 through which these screws extend being 30 slotted to permit of the adjustment above referred to. A set screw 44 extends through a lug 45 which projects laterally from the upper extremity of the bracket 6, and this set screw permits of very accurate adjustment of the bracket 41 with respect to 35 bracket 6, and thereby of the pivotal pin 39, with respect to pin 32. The rear extremity of the lever 38 is slotted as at 46 for the reception of the horizontal portion 47 of the U-bolt 16. The links 34 and 36 are 40 pivotally connected together to complete the toggle by means of a cross-pin 47, which is permanently secured in a rod 48. The rod 48 and the cross-pin 47 are movable through 45 a slot 49 in a link or bar 50; the outer extremity of said bar being pivotally connected at 51 in any suitable manner to the operating lever 5 of the switch. The slot 49 is reduced at its forward extremity 49' for 50 the reception of a flattened portion 52 of the rod 48 above referred to; this construction preventing said rod from rotating, and permitting only longitudinal displacement thereof. The slot 49 is somewhat greater in 55 width than the diameter of rod 48 to afford space for the reception of a helical spring 53, the forward extremity of which bears against the shoulders formed in the slot 49 by the reduction in the width thereof in the 60 manner above described, while the rear extremity 65

of this spring is preferably coiled around past the pin 47 so that the spring is firmly held in place. The forward extremity of the spring 53 is also preferably secured to the bar 50, as at 53'. Bar 50 70 rides freely in a slot 54 which extends through board 1 and the brackets 2 and 6; and the rear extremity of this bar is adapted for engagement with a spring latch 55 when the link has been driven almost completely 75 to its innermost position. This latch preferably consists simply of a somewhat Z-shaped spring which is secured to the block 8 in any suitable manner; the upper portion of the spring being turned over to 80 form a lip 56 which is adapted for engagement with the rear extremity of the lever 38; the lip 56 being adapted to enter the slot 46 and to thereby prevent the upward movement of lever 38 until the latch has 85 been disengaged therefrom. The lower rear corner of the lever 38 is preferably beveled as at 57 in order to insure the engagement of the latch with the slotted portion of said lever, when the lever is being swung downward into latch engaging position. The bar 50 may be guided laterally by the side walls of the slot 54, and its rear extremity 90 rides between the brackets 31.

The operation of the switch is as follows: 95 Assuming that the parts are disposed as shown in Fig. 1 with the latch in engagement with the lever 38, the toggle will be broken and the spring 53 will have urged the bar 50 and thereby the handle lever 5 100 substantially to its outermost position. By reason of the engagement of the U-bolt 16 with lever 38 the said bolt, and thereby the elastic contact blades carried upon the extremity thereof, will be in their lowermost 105 positions, the switch being open. Upon pressing the handle toward the board, bar 50 will be driven inwardly, and spring 53 will be placed under compression, thus bringing pressure, which will increase as 110 the handle is thrown inwardly, upon the pin 47 and thereby upon the toggle parts, tending to align the latter, and elevate the lever 38. This action, however, is resisted by the latch, and no movement of the flexible contacts will occur until the innermost 115 extremity or nose of the bar 50 encounters the latch. Thereafter, a further inward movement of the bar 50 effects a disengagement of the latch from lever 38, when the 120 spring 53, which is now under substantially its maximum compression becomes free to drive the pin 47 rearwardly, thereby abruptly elevating the lever 38 through the instrumentality of the toggles; resulting in 125 an almost instantaneous closure of the switch, and bending the legs of the elastic contact leaves 22 apart. When the switch is closed the toggle parts are substantially in alignment but are preferably not exactly 130

so, the pin 47 being driven rearwardly just beyond a line connecting the pivotal axes of links 34 and 36. A stop 57' being suitably positioned, as upon the lever 38, for limiting the rearward movement of the toggle parts. To open the switch, the handle is pulled outwardly and the first movement in that direction of the bar 50 enables the latch to spring back into its normal or engaging position; but since the pin 47 has previously been driven past the line connecting the centers of pins 32 and 37, the spring action of the elastic leaves 22, acting through the U-bolt, lever 38 and the toggle, will be sufficient to resist the forward movement of the pin 47 until the rear wall of the slot 49 comes into engagement with the rear end of the rod 48; the spring 53 being meanwhile placed under tension. Thereafter the outward movement of the bar 50 positively forces the toggle links out of alinement, breaking the toggle, and thereby enabling the spring 53 to abruptly effect the downward displacement of the contacts 22.

25 By adjusting the screw 44 upwardly or downwardly, the corresponding movement of pivot 39 will move the outer end of the lever 38 upwardly or downwardly about the pin 37 as a pivot, so that when the toggle is straightened the U-bolt will be drawn upward to a greater or less extent, said adjustment serving to increase or decrease the pressure between the elastic leaf contacts 22 of the stationary contacts 23.

35 It should be here noted that the lever 38 serves to multiply the comparatively slight movement of the pin 37 so as to produce a relatively long movement of the movable contacts in practically the same lapse of time as would be consumed for a short movement without the lever. A more rapid make and break is thus secured.

Normally the momentum of the moving parts will be sufficient to effect the reengagement of the latch with its lever. If, however, it be desired to insure positively that such latching action shall invariably occur even if the handle 5 be drawn outwardly very slowly, light compression springs 58

45 may be provided on the depending arms of the U-bolt 16, intermediate the thimbles 10 and the nuts 20 upon the upper side of the block 18, which springs will exert sufficient effort upon the bolt 16 and thereby upon the lever 38 to insure the engagement of latch 55 and lever 38; the handle of course being correspondingly driven to its outermost position. I prefer also to provide bumper springs 59 upon the respective arms

55 of the U-bolt above the block 8, these springs never being under any material compression, but merely serving to reduce the shock due to the forceful and rapid displacement of the bolt and its attendant contacts when the

60 switch is opened. To this end, the respec-

tive legs of the bolt 16 may carry washers 60, the said legs being perforated for the reception of driven pins 61 above said washers.

Several advantages accrue from constructing a switch in the manner which I have described. In the first place, both the making and the breaking of the circuit are extremely rapid. Further the switch parts employed are relatively inexpensive to manufacture; and the switch elements proper may all be disposed upon the rear side of the board, enabling them to be inclosed in suitable casings 62 while all that is visible of the switch upon the front of the board is its handle, the supporting bracket therefor, and a small portion of the bar 50. The electrical connections are readily made to the switch by means of the terminals 29; and while I have shown a four-pole switch, it is obvious that my invention may be employed in connection with switches of other types. The toggle action in connection with the yieldingly mounted rod and latch is regarded as of considerable importance, as is also the particular co-action between the elastic contact leaves and the toggle, with the further positive breaking of the toggle by the outward movement of the handle.

I particularly direct attention to the fact that my switch not only opens rapidly but closes with substantially equal rapidity, even when the operating handle is moved quite slowly. Further the switch while adapted to carry heavy currents, if made of proper proportions, occupies but little space upon the switchboard by reason of the rearward disposition of its elements.

Having described my invention, I claim:

1. In an electric switch, a plurality of contact elements and mechanism for abruptly placing said elements in contact with each other, said mechanism including pivotally mounted toggle parts, a spring adapted to exert pressure upon at least one of said parts, for driving their pivotal points substantially into alinement, means for positively opposing said pressure, and means for displacing said opposing means.

2. In an electric switch, a plurality of contact elements and mechanism for abruptly placing said elements in contact with each other, said mechanism including toggle forming parts, a spring adapted when stress is applied thereto to exert pressure upon at least one of said parts, for driving them into substantial alinement, means for opposing said pressure, and means for displacing said opposing means.

3. In an electric switch, a plurality of contact elements and mechanism for abruptly placing said elements in contact with each other, said mechanism including a toggle, said toggle being normally broken when the switch is open, a spring for dispos-

ing parts of said toggle in substantial alinement, a latch for opposing said spring, and means for disengaging said latch.

4. In an electric switch, a plurality of contact elements and mechanism for abruptly placing said elements in contact with each other, said mechanism including a lever, a support, thrust connections between said lever and said support adapted, when operated, to displace said lever with respect to said support, means for placing said connections under stress, normal movement of said connections under said stress displacing said lever, means for holding said lever against displacement, and means for disengaging said holding means when said stress has attained substantially a maximum.

5. In an electric switch, a plurality of contact elements and mechanism including an actuating handle for abruptly separating said elements regardless of the speed of the switch opening movement of said handle, said mechanism comprising pivotally connected parts constituting a toggle, said contact elements when in contact being normally held firmly together by said toggle, and means for breaking said toggle, said means being movable initially by a movement of said handle and being adapted for movement substantially independently of said handle after such initial movement.

6. In an electric switch, a plurality of contact elements and mechanism including an actuating handle for abruptly separating said elements regardless of the speed of the switch opening movement of said handle, said mechanism comprising a support, a lever mounted independently of said support and thrust connections between said lever and said support for holding said lever spaced from said support, said thrust connections normally resisting initial switch opening movement of said lever toward said support when said contact elements are in operative relationship.

7. In an electric switch, a plurality of contact elements and mechanism for abruptly placing said elements in contact with each other, said mechanism including resilient means adapted to move said contacts together; a latch for positively retaining said contacts separated; a carrier for said spring having a recess adapted to receive said spring, said carrier being bodily movable toward said latch for compressing said spring; and means slidable in said carrier adapted to retain said spring in said recess; said carrier being adapted to directly strike said latch to disengage said latch from retaining position when said spring is compressed.

8. In an electric switch, fixed contact elements, resilient contact elements movable with respect to said fixed elements, a lever

for moving said resilient elements, a fixed support, connections between said lever and said support, and handle operated means for varying the disposition of said connections, said connections being normally maintained in substantial alinement with each other when the contact elements are in operative relationship by the pressure of said resilient elements against said fixed elements operating through said lever.

9. In an electric switch, an insulating support, contacts mounted thereon, a contact-carrying part, said part being movable in guided relation to said support, a pivoted member adapted to move said contact-carrying part, means for abruptly displacing said pivoted member, said means including toggle parts, an energy storing device for operating said toggle parts, a latch for restraining movement of said parts, and means for releasing said latch when the energy stored in said device has attained substantially a maximum.

10. In an electric switch, an apertured insulating base, fixed contacts carried thereby, a U-bolt extending through the apertures in said base, contact pieces carried by said U-bolt, an actuating lever for said bolt, linked connections between said lever and base, a handle, a link between said handle and said connections, a spring normally adapted to actuate said connections, a latch for said lever, said link being adapted to compress said spring when the handle is operated in one direction, and means for releasing said latch when said link has been further driven in the same direction.

11. In an electric switch, a plurality of contact elements and mechanism for abruptly placing said elements in contact with each other, said mechanism including resilient means adapted to move said contacts together; a latch for positively retaining said contacts separated; and means bodily movable toward said latch for placing said resilient means under stress, said last mentioned means being adapted to directly strike said latch to disengage said latch from retaining position when said resilient means has attained substantially a maximum stress.

12. In an electric switch, a plurality of contact elements and mechanism for abruptly placing said elements in contact with each other, said mechanism including a compression spring adapted to move said contacts together; a latch for positively retaining said contacts separated; and a carrier for said spring bodily movable toward said latch for compressing said spring, said carrier being adapted to directly strike said latch to disengage said latch from retaining position when said spring is compressed.

13. In an electric switch; fixed contact elements; resilient contact elements movable with respect to said fixed contact elements;

a fixed support; connections between said fixed support and said movable contact elements adapted to be maintained in one position by the pressure of said movable contact elements against said fixed contact elements for preserving the pressure between said contact elements; and means for adjusting said pressure.

14. In an electric switch; fixed contact elements; resilient contact elements movable with respect to said fixed contact elements; a fixed support; connections between said fixed support and said movable contact elements including a toggle; means for multi-

plying the thrust of said toggle upon said movable contact elements, said toggle being adapted to be maintained in one position by the pressure of said movable contact elements against said fixed contact elements for preserving the pressure between said contact elements; and means for adjusting said pressure.

In witness whereof, I subscribe my signature, in the presence of two witnesses.

JOHN A. COLE.
